UNITED STATES PATENT OFFICE.

HENRY KIELBERG, OF MARTINS FERRY, OHIO, ASSIGNOR TO WHITAKER-GLESSNER COMPANY, OF WHEELING, WEST VIRGINIA, A CORPORATION OF WEST VIRGINIA.

GRID FOR GAS AND OIL STOVES.

Application filed October 5, 1921. Serial No. 505,458.

To all whom it may concern:

Be it known that I, HENRY KIELBERG, a citizen of the United States of America, and resident of Martins Ferry, county of Belmont, and State of Ohio, have invented certain new and useful Improvements in Grids for Gas and Oil Stoves, of which the following is a specification.

This invention relates to stove grids of the general character commonly employed for seating within the usual circular holes of stove tops, and it has for its primary object to provide a grid constructed of a sheet-metal stamping pressed or drawn into a novel form which affords the requisite rigidity and strength and which is adapted to successfully resist the usual tendency to become warped from heat.

A further object is to provide a grid which, in addition to being strong and durable, is light in weight and is comparatively inexpensive to manufacture.

In describing the invention in detail, reference is herein had to the accompanying drawings, in which—

Figure 1 is a top plan view of the invention, and—

Figure 2 is a section of the same on line 2—2, Fig. 1.

The grid constituting the invention is fabricated from a circular sheet-metal plate or stamping and comprises a plurality of concentric upwardly pressed beads, as 2 and 3, each substantially semi-cylindrical in cross section, connected by relatively spaced radial ribs 4, also upwardly pressed into approximately semi-cylindrical form, said ribs being separated by openings or perforations 5. A central opening 6 is encircled by the

inner bead 3 which may have shoot tongues 7 projecting radially inward therefrom. Encircling the outer bead 2 is a flat terminal flange or rim 1 for resting upon the usual seating ledge which surrounds the top hole of a stove.

The convex top surface of the beads 2 and 3, the ribs 4 and the tongues 7 are disposed in a common horizontal plane, as shown in Fig. 2.

As is apparent, the grid described may be readily produced by simple and common pressing or drawing methods, and, consequently, is relatively inexpensive to manufacture. Moreover, the concavo-convex form of the various parts of the structure provides not only for strength and rigidity, but also for great resistance against warping.

What is claimed is—

As a new article of manufacture, a one-piece fretwork grid for the circular holes of stove tops, said grid being stamped from sheet metal and consisting of concentrically disposed rings, relatively spaced radial bridges joining said rings, said rings and said bridges being pressed into substantially semi-cylindrical form in cross section, the spaces between said rings and said bridges being wholly open to the passage of flame, and a circular seating flange extending outwardly from the outer of said rings.

In testimony whereof, I affix my signature in presence of two subscribing witnesses.

HENRY KIELBERG.

Witnesses:

L. B. WOOD,
H. E. DUNLAP.
